DESIGN FOR A CANDLE HOLDER

Joseph Brenowitz and Ida Gottlieb,
New York, N. Y.

Application July 15, 1936, Serial No. 63,872

Term of patent 7 years

To all whom it may concern:

Be it known that we, Joseph Brenowitz and Ida Gottlieb, both citizens of the United States, and both residing at New York city, in the county of Kings and State of New York, have invented a new, original, and ornamental design for a Candle Holder, of which the following is a specification, reference being had to the accompanying drawing, forming part thereof.

In the drawing:

We claim:

The ornamental design for a candle holder, as shown.

JOSEPH BRENOWITZ.
IDA GOTTLIEB.
